C. MULLER
PISTON GROOVING TOOL,
APPLICATION FILED APR. 9, 1919.

1,346,838.

Patented July 20, 1920.

UNITED STATES PATENT OFFICE.

CHRISTIAN MULLER, OF FALL RIVER, MASSACHUSETTS.

PISTON-GROOVING TOOL.

1,346,838.

Specification of Letters Patent. Patented July 20, 1920.

Application filed April 9, 1919. Serial No. 288,764.

To all whom it may concern:

Be it known that I, CHRISTIAN MULLER, a citizen of the United States, residing at Fall River, county of Bristol, Commonwealth of Massachusetts, have invented certain new and useful Improvements in Piston-Grooving Tools, of which the following is a specification.

This invention relates to grooving tools and particularly to a regrooving tool for the ring channels of engine pistons and the like.

The difficulty of properly centering and setting up pistons in a lathe and in fact the frequent lack of an available lathe for such purpose has made the matter of fitting new rings to pistons an expensive and annoying incident especially to owners in the upkeep of their automobiles.

It is therefore highly desirable that the ordinary garage or repair man have some means for regrooving pistons for the fitting of piston rings which can be depended upon for service without too much disassembling of the parts of the motor and without too much dependence upon highly skilled labor.

To the end therefore of providing a tool capable of such uses, I have devised my present invention. In this I have provided an extremely simple and inexpensive and yet highly efficient tool capable of operation by the average mechanic. In many cases this tool can be employed without completely removing the piston and without removing the connecting rod from the piston. The construction and operation of my tool will be more fully described in the specification which follows.

In the accompanying drawings I have shown an embodiment which I have found well adapted to the ends sought and which will regroove pistons rapidly and accurately so that standard piston rings may be applied without delay and at little cost. Throughout the specification and drawings like reference numerals are employed to indicate corresponding parts. In the drawings:

Figure 1 is a side elevation of a tool in accordance with my invention.

Fig. 2 is a central sectional view thereof.

Fig. 3 a plan view.

Fig. 4 a fragmentary detail of a portion of the inner face of my tool, and

Fig. 5 is a diagrammatic view showing the position of the tool in the piston groove.

My tool comprises a flexible bearing band comprising a flexible base segment 1, a pair of detachable adjustable segments 2 and 3 which are also preferably flexible. The section 1 is provided with a short curved bracket 4 suitably welded or riveted to the section 1. On the bracket is a split clamp member 5 set up by a screw 6 passing through opposed ears and adjustably gripping a tool holder 7 having a squared cutting tool 8. The member 1 is opened at 9 for observation of the groove G of the piston P. The members 2 and 3 are detachably connected to the section 1 by hooked shaped portions 2¹, 3¹, engaging with reversibly hooked portions 1¹. At their opposed ends the sections 2 and 3 are provided with out-turned portions forming ears which may be set up by a wing nut 10 on a threaded stem 75 11. The out-turned portion of the member 2 may be carried out and rolled in a handle on grip 12.

The members 2 and 3 are also provided with elongated cam guiding members 13, the stems of which pass through the members 2 and 3, and through split clamp members 14 mounted on the outer faces of the sections 2 and 3. The stems of the cam 13 are provided with handles 15 by which the cam 85 guiding members 13 may be adjusted to snugly fit within the grooves G of the piston ring for steadyng the tool on the piston.

In operation my tool is set up with segments 2 and 3 of proper length to snugly fit the diameter of the piston and the tool 8 is inserted in the groove to be re-cut. The wing nut 10 having been set up with the cams 13 also in the groove and with the band portion of the tool snugly but movably embracing the piston, the cams 13 are set transversely in the groove so as to provide a steadyng bearing at two points opposite to the tool 8. The tool 8 is now turned within the groove of the piston until its edges begin to take on the worn edges of the groove. The tool 8 with its holder 7 is now rotated on the piston until the groove has been cut all the way around and is then clamped in place. The tool 8 may be fed in or further rotated on its axis to give a wider cut if necessary to complete the rectification of the groove walls or their enlargement to receive the particular size of ring which it is wished to insert.

Various modifications may obviously be made in the construction and arrangement

of parts. The tool holder may be modified and the form and arrangements of the segments may be varied, as also their number. All these and various other departures from the particular form shown may be made without departing from the spirit of my invention if within the limits of the appended claim.

What I therefore claim and desire to secure by Letters Patent is:

A regrooving tool for pistons, comprising

a piston encircling guide member, a tool radially and rotatably adjustable therein and opposed groove engaging guide members also rotatably adjustable therein.

In testimony whereof I affix my signature in presence of two witnesses.

CHRISTIAN MULLER.
